UNITED STATES PATENT OFFICE

126,273

DESIGN FOR A SHIRT OR SIMILAR ARTICLE

Elsie Swan, Los Angeles, Calif., assignor to Hollywood Rogue Sportswear, Inc., Los Angeles, Calif., a corporation of California

Application February 7, 1939, Serial No. 82,850

Term of patent 3½ years

To all whom it may concern:

Be it known that I, Elsie Swan, a citizen of the United States and a resident of the city of Los Angeles, in the county of Los Angeles and State of California, have invented a new, original, and ornamental Design for a Shirt or Similar Article, of which the following is a specification, reference being had to the accompanying drawing, forming part thereof, in which:

Fig. 2 is a rear view thereof.

I claim:

The ornamental design for a shirt or similar article, substantially as shown.

ELsie SWAN.
